UNITED STATES PATENT OFFICE.

EDWIN SMEDLEY, OF DUBUQUE, IOWA, ASSIGNOR TO THE NATIONAL IRON AND BRASS WORKS, OF SAME PLACE.

VERTICAL DRILL.

SPECIFICATION forming part of Letters Patent No. 313,114, dated March 3, 1885.

Application filed March 14, 1884. (No model.)

To all whom it may concern:

Be it known that I, EDWIN SMEDLEY, of Dubuque, in the county of Dubuque and State of Iowa, have invented certain new and useful 5 Improvements in Vertical Drills; and I do hereby declare that the following is a full, clear, and exact description of the invention, which will enable others skilled in the art to which it appertains to make and use the same, 10 reference being had to the accompanying drawings, and to letters of reference marked thereon, which form a part of this specification.

My invention relates to the mechanism for allowing a quick return-feed, and will be 15 readily understood from the following description.

In the drawings, Figure 1 illustrates a side elevation of a vertical drill-press embodying my invention. Fig. 2 is a vertical section 20 through the line $o\ o$ of Fig. 1; Fig. 3, a horizontal section on an enlarged scale through the line $y\ y$ of Fig. 1, and Fig. 4 an enlarged view of the slide f and its adjacent devices.

Upon bearings in the horizontal bracket 1, 25 through which the drill-stock 2 works, is a small shaft, a , having a lever-handle, b , at one of its ends, and an eccentric-pin, c , at its other end, and this pin is permitted a limited range of motion when this shaft is turned 30 by its handle, the pin d restricting its movement in one direction, and the pin e restricting it in the other direction, for purposes presently to be stated. This eccentric-pin c works in a horizontal slot made in a vertically-mov- 35 able head or slide, f , arranged to move in dovetailed or other guides, $g\ g$, which are shown enlarged in Fig. 3. On this slide f is a shaft, h , carrying a worm, i , the end of the shaft having a wheel and handle j for operating it. When the handle b is down against the stop d , the eccentric-pin c has passed a little beyond the upper center, or its highest throw, thus carrying the screw or worm i into full gear or engagement with the worm-wheel 40 or gear k on the shaft l , and which shaft carries a small pinion, m , which engages with the rack m' . n is a hand-wheel for actuating this shaft l and its pinion m when the worm i and the worm-wheel k are thrown out of engagement 45 with each other.

The operation is as follows: When it is desired to give a powerful but slow feed, the handle b is brought down against the stop d , as above stated. The eccentric-pin c , by means of such action, lifts the slide f and causes the worm i and its worm-wheel k to engage with each other, and then the operator, by using the hand-wheel j , can produce a very slow feed of the drill, for the worm i gives but a slow revolution to the wheel k and its shaft, 55 and thus the pinion m gives but a slow movement through the rack m' to the drill or bit-stock m^2 . It will also be observed by reference to the lines $x\ x$ and $x'\ x'$ in Fig. 4 that when the parts are in the position shown in 60 that figure the center of the pin c has passed beyond the vertical line $x\ x$ and reached a point in the line $x'\ x'$. This position serves to keep the pin in its proper place when strain is put upon the screw or worm i , for any strain 65 then brought on the pin c would only tend to keep the handle b against the stop d , and this is the object of placing the stop d in such a position as that it shall not arrest and hold the handle b until the eccentric shall have 70 passed the center.

When it is desired to gain or insure a quick return to the drill, the operator merely throws the handle b up until it comes to the stop e . This revolves the shaft a and moves the pin 80 c downward, thus carrying downward also the slide f and the worm or screw i until the latter becomes disengaged from or out of gear with the worm-gear k . This sets the gear k and its shaft l entirely free from any relation 85 to or connection with screw i , and the operator can then effect a quick return of the drill, as well as an excellent quick feed for light work by means of the hand or lever wheel n' .

The other parts illustrated in the drawings 90 need not be particularly described in the present application.

It will be seen that as the eccentric-pin c works in a horizontal slot in the slide f it serves positively to lower the worm out of gear 95 as well as to raise it into engagement with its gear k ; that as both journals of the worm-shaft h are in the same vertically-sliding piece f their relative positions cannot change, but remain a constant; that as this slide f is held 100

in vertical parallel guideways it must always move in the same right lines, and that the slide when adjusted holds the worm firmly to its work.

5 I claim—

As a means for effecting a variable feed and permitting a quick return-feed in vertical drills, the sliding head *f*, constructed as described, and arranged to be moved in fixed 10 vertical guideways *g*, and provided with two

shaft-bearings and a horizontal slot, and having the worm-shaft supported in said bearings, and having a handled shaft, *a*, provided with an eccentric-pin working in such slot, these parts being constructed, arranged, and 15 operating as and for the purpose set forth.

EDWIN SMEDLEY.
